(57) CLAIM

The ornamental design for a mattress cover, as shown and described.

DESCRIPTION

FIG. 1 is a plan view of a mattress cover for a mattress showing my new design in accordance with an embodiment; and,

FIG. 2 is a plan view of a mattress cover for a mattress showing my new design in accordance with another embodiment.

The broken lines represent features of an exemplary mattress including the mattress cover that form no part of the design.

1 Claim, 2 Drawing Sheets
